UNITED STATES PATENT OFFICE.

WILHELM LESSING, OF GESECKE, GERMANY.

PROCESS OF BURNING CEMENT, GYPSUM, &c.

SPECIFICATION forming part of Letters Patent No. 678,412, dated July 16, 1901.

Application filed April 23, 1900. Serial No. 14,036. (No specimens.)

To all whom it may concern:

Be it known that I, WILHELM LESSING, a subject of the Emperor of Germany, residing at Gesecke, Westphalia, Germany, have invented a new and useful Process of Burning Cement, Gypsum, or the Like, of which the following is a specification.

Revolving furnaces for this purpose require, of course, an inner jacket of fireproof material. When the material passes through in pieces, each piece rubs against the fireproof jacket, so that in a short time the latter is entirely worn away and has to be replaced in order to prevent the metal jacket of the furnace from being burned. If, however, it is desired to completely calcine cement or the like in an inclined revolving furnace, it is necessary to move the material through very slowly or to cause it to pass successively through several such revolving furnaces until the degree of heat required for complete calcination is reached, so that in this case also the slags melt together and have to be broken and ground when cool. The latter effect of smelting together is produced in a still greater degree if the raw material is introduced into the furnace in form of powder instead of pieces in order to save the fireproof jacket. Material in the form of powder has a far greater tendency to cake under the influence of high temperature than materials in pieces, as is known. Burning powdered material in such furnaces had, therefore, the further disadvantage that caked material adhered to the inner jacket of the furnace and that through the continual accumulation of larger and larger quantities of the adhesive substance the orifice of the furnace was entirely closed and no more material could be put in. With this method, likewise, the heat of the gases of combustion escaping from the furnace by the chimney remained unutilized. Suggestions for the utilization of these gases for the preliminary heating of the air for combustion have already been made, (see United States Patent No. 457,589,) the idea being to cause the air to pass through a winding pipe passing through the smoke-box or through the chimney itself, and therefore surrounded by the gases of combustion. On the other hand, however, this method does not by any means utilize the whole of the heat contained in the

gases of combustion, and, on the other hand, the burned material is not sufficiently cooled, as the current of air which is intended to cool it is itself already considerably heated; and therefore not capable of absorbing much more heat. It is also obvious that even when the burned material is cooled by means of fresh air in the manner hereinbefore described the cooling is by no means complete and that a larger proportion of the heat of the material (about two-thirds) remains unutilized.

The object of the present invention is a process for continually burning cement, gypsum, or the like, in which also a revolving furnace is used and the air sucked in by the furnace is intensely heated in advance by being employed for cooling the burned material, but which process differs very considerably from all hitherto-known methods of burning, in that the raw material is introduced after it has been ground into a revolving furnace, which only brings it approximately to a white heat, and is then transformed, still in a powdered condition, to a high-shaft furnace, in which it trickles slowly downward between suitably-arranged impediments—such as, for instance, cones—against a column of flame, and is thus completely burned without being baked together into a compact mass. It is then caused to move against the current of air which supplies the flame with oxygen, and is thus to some extent cooled. Instead, however, of the burned material then being left to cool completely by itself it is according to this process transferred into several revolving cylinders or drums, in which steam-producing apparatus are arranged in such a manner that they are heated in order to produce steam by the still very hot burned material, and by thus withdrawing heat from the latter cool it entirely. The cooling process is further accelerated thereby, so that the burned material leaves the drums at the place where fresh water for producing steam enters. To render the product ready for transport and use, it is then only necessary to pulverize it finely. By the present process the heat of the escaping gases is also utilized to a far greater extent than was the case hitherto, these gases also being conducted through inclined cylinders, thereby drying the unground raw material,

or, if that is unnecessary, heating steam-producing apparatus.

In the annexed drawings the entire plant necessary for carrying out the present process is represented.

Figure 1 is a longitudinal section of the entire furnace arrangements. Fig. 2 is a front view of the furnace; and Fig. 3, a section through the middle of the revolving furnace, showing the manner in which it is suspended. Fig. 4 is a plan view of the entire furnace plant. Fig. 5 is a section of the revolving furnace on a larger scale, and Fig. 6 is a section of the drying cylinders or drums.

15 The broken raw material is introduced through the funnel *a* into the revolving warming and drying drums *b* and *c*, in which it is warmed and dried. These processes are furthered by the drums *b* and *c* being provided with longitudinal ribs, which at each revolution carry the raw material up and let it fall again, and thus continually expose it to the hot current which passes through the drums from the furnace *d* until the raw material has become porous and suitable for being ground. From the drums the raw material falls on the incline *e*, which ends in the shaft of an elevator. The raw material is then raised by means of elevators, crushed, 30 and ground. The ground material is then introduced through the funnel *f* into the furnace *d*, through which it is made to pass in the usual manner. From the furnace *d* the material is passed to the shaft-furnace *i*. In 35 the upper part of the latter a cone *n* or the like is provided, which disperses the ground material evenly and breaks its fall to some extent. Through the pipe *l* heated gas is conducted to the shaft-furnace and through the cylinder *k* heated air. These mingle in the lower part of the shaft-furnace and the hot mixture of air and gas feeds an ascending column of flame, which prevents the ground material from descending too rapidly, and 40 enters the revolving furnace *d*. According to requirements a mixture of hot air and gas can be introduced into the furnace *d* through the pipe *m*. As has already been mentioned, the ground burned material is dispersed and 45 trickles downward in the furnace *i*. Consequently the column of flame moves against the material, by which means the latter is maintained for a longer period at incandescent heat and is completely burned without 50 the possibility of its caking.

Like the cylinders *b* and *c* and the furnace *d*, the cylinder *k* is inclined, and its interior surface is also provided with longitudinal ribs. It is of considerable length. At the 55 moment of entering this cylinder *k* from the shaft-furnace the material has attained the highest degree of temperature required. The lifting up and dispersal of the material by the longitudinal ribs of the cylinder *k* cause the smallest particles of the material to come into contact with the current of fresh air, which enters through the holes *o*, and also

cause the said current of air to become heated and the material to move forward till it reaches the holes *o*, through which and the funnel *u* it falls into the drums *v*. The holes *o* can be made larger or smaller, according to requirements, by means of suitable sliding devices.

Inside of the drums *v* steam-producing apparatus are provided—in the present instance, revolving tubular boilers *j*. These are somewhat inclined and adjustable. The burned material cools against the boiler-tubes containing water and gradually moves in consequence of the revolving motion toward the holes *y*, through which its falls, completely cooled, and is then transferred to the grinding and shifting machine. In order to further the forward movement of the material in the drums *v*, the interiors of the latter are likewise provided with longitudinal ribs. These ribs lift the material and then let it fall back again. The heat of the material being cooled gradually converts the water in the boilers 90 into steam. The steam is then conducted by the tubes *x* or the like to a steam-accumulator and can then be utilized for driving the engine employed.

In order to secure the complete utilization 95 of the gases of combustion, the latter can be passed from the drums *b* and *c* to a third revolving drum, in which they are used to dry some material, such as marl, clay, or the like.

Before the gases escape into the chimney 100 the dust produced by this drying process is deposited in a special dust-receptacle.

Instead of the drums *b*, *c*, and *s*, horizontal steam-producers can of course be provided, which are heated by means of the gases escaping from the furnace, so that in this case also the gases of combustion are utilized.

Having now described my invention, what I claim as new, and desire to protect by Letters Patent, is—

1. The herein-described process for burning cements, gypsum, &c., which consists in grinding the raw material and heating this product to a white heat, dropping it downwardly against a column of flame, and then 115 utilizing it in its intensely-heated condition for generating steam to be used for the treatment of further material, substantially as and in the manner specified.

2. The process for burning cements, gypsum, &c., which consists in warming and drying broken raw material, then grinding and heating and slowly dropping against a column of fire, then cooling and utilizing the resulting heat for generating steam and for the preliminary warming of the material, substantially as set forth.

Berlin, Germany, this 24th day of March, 1900.

WILHELM LESSING.

In presence of—

WOLDEMAR HAUPT,
HENRY HASPER.
